J. ADAMS

GATE

Filed April 23, 1924

Jesse Adams

Inventor

By

Clarence O. Brian

Attorney

UNITED STATES PATENT OFFICE.

JESSE ADAMS, OF NILWOOD, ILLINOIS.

GATE.

Application filed April 23, 1924. Serial No. 708,446.

To all whom it may concern:

Be it known that I, JESSE ADAMS, a citizen of the United States, residing at Nilwood, in the county of Macoupin and State 5 of Illinois, have invented certain new and useful Improvements in a Gate, of which the following is a specification.

This invention relates to new and useful improvements in gates and has for its principal object to provide a simple and efficient means whereby the locking means provided for cooperation with the gate may be released so as to permit the free swinging movement of the gate.

One of the important objects of the present invention is to provide a device of the above mentioned character, wherein means is associated with the gate for releasing the locking means, said means being 20 operable from either side of the gate.

A still further object of the invention is to provide a gate of the above mentioned character, wherein the locking means provided therefor may be released without the loss of time or labor, the parts being so arranged as to render the device simple in construction, inexpensive, strong and durable and furthermore adapted for the purposes for which it is designed.

Other objects and advantages of this invention will become apparent during the course of the following description.

In the accompanying drawing forming a part of this specification and in which like numerals designate like parts throughout the same:

Figure 1 is a side elevation of my improved gate, and

Figure 2 is a longitudinal section taken 40 approximately on line 2—2 of Figure 1.

In the drawing wherein for the purpose of illustration is shown the preferred embodiment of my invention, the numerals 1 and 1' designate a pair of spaced posts.

Carried by the post 1 is the locking means for the bolt of the gate and the same comprises a supporting bracket 2 which is preferably formed of sheet metal, the same extending through the fence post 1 in the manner shown in Figure 2. The lateral extensions formed on the inner end of the sup-

porting bracket 2 have the pins 3 extending transversely therethrough adjacent the ends thereof and adapted to be loosely supported on the pins 3 in the lateral extensions 4 and 55 supporting bracket 2 are the locking rings 5. These rings are of such size as to be spaced from each other and normally the rings extend downwardly from the lateral extensions of the supporting brackets so as 60 to be in an operative and in locked engagement with the bolt of the gate hereinafter to be more fully described.

The other post 1' has extending inwardly therefrom adjacent the upper end thereof 65 the hook 6 while extending inwardly from the lower portion of the post 1' are the spaced brackets 7. Disposed between the posts 1 and 1' respectively is the gate designated generally by the numeral 8 and the 70 same is of the usual construction. The rear end of the gate is provided with the strap 9 adjacent the upper end thereof for engagement with the hook 6 whereby a hinged connection is provided. The lower rear end 75 of the gate 8 has extending outwardly therefrom on its opposite side the plate 10 the outer free ends of which terminate into the curved portion 11 for engagement with the brackets 7 in the manner clearly shown in 80 Figure 2 of the drawing whereby a hinged connection for the lower end of the gate is also provided.

Extending outwardly from the forward end of the gate 8 is the bolt 12 and the same 85 is normally adapted to be disposed between the locking rings 5 in the manner illustrated in the drawing so as to hold the gate 8 in a locked position and against swinging movement. For the purpose of releasing the locking rings 5 from engagement with the bolt 12 of the gate 8 so that the latter may swing to an open position, I provide a simple and efficient means the construction of which will be presently described.

A pair of plates such as are shown at 13 in the drawing are pivotally supported at their rear ends on opposite sides of the forward end of the gate 8 in the manner shown at 14. The forward ends of the arms 13 100 extend outwardly adjacent the bolt 12 in the manner clearly illustrated in Figure 2

of the drawing. The forward ends of the arms are further disposed below the rings 5 so as to cooperate therewith in releasing the rings from engagement with the bolt in the manner which will hereinafter be more fully described. The rear portions of the arms are provided with the extensions 15 and the ends of the extensions terminate in the eye portions 16. Cooperating with the eye portions 16 formed on the rear ends of the extensions 15 of the arms 13 are the forked ends 17 of an elongated rod 18.

This rod 18 extends rearwardly and longitudinally on the gate 8 in the manner clearly illustrated and between the vertical braces 19 arranged on opposite sides of the intermediate portion of the gate 8 in the manner illustrated in the drawing. A supporting block such as is shown at 20 is mounted on the gate 8 and the same comprises a pair of complementary sections which are secured to the opposite sides of one of the longitudinally extending rails of the gate. The block 20 is further supported on the gate 8 adjacent the central vertical braces 19.

Pivotedly supported on the forward end of the block 20 on each of the complementary sections 21 and 22 thereof respectively are the bell crank levers 23 and 24 respectively. The longer arms 25 and 26 respectively of the bell crank levers 23 and 24 extend outwardly on opposite sides of the gate 8 and are spaced therefrom in the manner as illustrated in Figure 2. The inner shorter arms 27 and 28 of the bell crank levers 23 and 24 respectively are connected to the rod 18 adjacent the inner end thereof. The connection of the shorter arms of the bell crank levers to the rod 18 is shown at 29 in the drawing.

Pivotedly supported on the gate 8 on each side of the vertical brace 19 are the levers 30 and 31 respectively. The pivot means therefor being illustrated by the numeral 32. The levers are preferably pivoted adjacent their lower ends and their lower ends are adapted to be disposed between the longer arms of the bell crank levers and the vertical braces 19 in the manner clearly illustrated in Figure 2. The upper ends of the levers extend adjacent the top of the gate and provide a means for manually controlling the operation of the releasing means for the locking rings 5. The operation of the releasing means which is controlled by the manual operation of the levers 30 and 31 will hereinafter be more fully described.

Pivotedly supported on the rear portions of the complementary sections 21 and 22 of the blocks 20 are an additional pair of bell crank levers 33 and 34 respectively. The shorter arms of the bell crank levers are connected to the inner end of the rod

18 as shown at 35 while the longer arms of the bell crank levers are disposed outwardly on opposite sides of the gate and are adapted to cooperate with the additional levers 36 and 37 respectively which are pivoted at their upper ends as shown at 38 on opposite sides of the gate.

The operation of the releasing means may be briefly stated as follows: Normally the gate is in locked position as shown in the drawing. Either the lever 30 or the lever 36 which are mounted on one side of the gate may have their free ends pushed inwardly and the actuation of the levers in this manner will cause either of the bell crank levers 23 or 33 to cause the forward movement of the elongated rod 18. The forward movement of the rod 18 will cause a subsequent upward swinging movement of the arms 13 on their pivots 14 and as the arms are raised upwardly, the same will cause an upward movement of the locking rings 5 in the lateral offset portions 4 of the supporting bracket 2 and thus the locking rings come out of engagement with the bolt 12 whereby the gate 8 may be swung in a horizontal plane to an open position. It is of course to be understood that the rod 18 is to be actuated by the bell crank levers from either side of the gate, the parts being so arranged as to insure the proper operation of the rod 18 whenever the levers on either side of the gate are operated. The provision of the levers 36 is to provide a means whereby the gate may be opened by a vehicle without necessitating the driver of the vehicle of having to leave his seat in order to release the locking means of the gate. The levers 30 and 31 are adapted for manual actuation in order to swing the gate to an open position.

It will thus be seen from the foregoing description, that a gate has been provided wherein the bolt releasing means therefor will be positive and efficient in its operation and the simplicity of the same enables a gate to be provided with such an attachment at a very low cost, the same will also be strong and durable.

While I have shown the preferred embodiment of my invention, it is to be understood that various changes in the size, shape and arrangement of parts may be resorted to without departing from the spirit of the invention and the scope of the appended claim.

Having thus described my invention, what I claim is:

In a structure of the class described, a gate provided at its forward edge with a retaining bolt, a pair of arms pivoted on the gate and extending outwardly therefrom on opposite sides of said bolt, the inner ends of said arms being provided with crank extensions, a longitudinally movable operating

rod having a fork formed at its outer end, the arms of said fork being connected at their free ends to said crank extensions, a pivotally mounted bell crank at the inner 5 end of said rod, the short arm of said bell crank being pivotally connected with said rod, and an operating lever pivoted on said

gate and adapted for engagement with the free end of said bell crank for actuating the same and said rod, whereby to control 10 said arms.

In testimony whereof I affix my signature.

JESSE ADAMS.
